United States Patent Office

Des. 190,957
Patented July 25, 1961

190,957

FURNITURE LEG

David Imber, 1324 Plimpton Ave., Bronx, N.Y., and Sol J. Imber, 3715 Libby Lane, Levittown, Long Island, N.Y.

Filed Dec. 6, 1960, Ser. No. 63,150

Term of patent 14 years

(Cl. D33—14)

Fig. 1.

Fig. 2.

Fig. 3.

Fig. 4.

FIG. 1 is a front elevational view of a furniture leg showing our new design;

FIG. 2 is a side elevational view;

FIG. 3 is a top plan view; and

FIG. 4 is a rear elevational view.

This application is a continuation in part of our application Serial No. D. 61,185, filed July 1, 1960.

We claim:

The ornamental design for a furniture leg, as shown and described.
